UNITED STATES PATENT OFFICE.

ARTHUR HENRY KINCEY, OF BIRKENHEAD, ENGLAND.

DESIGN FOR A CLIP-HOOK.

SPECIFICATION forming part of Design No. 32,690, dated May 22, 1900.

Application filed January 17, 1900. Serial No. 1,802. Term of patent 14 years.

To all whom it may concern:

Be it known that I, ARTHUR HENRY KINCEY, a subject of the Queen of Great Britain, and a resident of Birkenhead, (Prenton,) in the county of Chester, England, have invented and produced a new, useful, and original Design for a Clip-Hook, of which the following is a description, reference being had to the accompanying drawings, wherein—

10 Figure 1 is a side elevation of a clip-hook embodying my design, and Fig. 2 is a perspective view of the same.

The leading feature of my design consists in the upper member, the L-shaped member 15 depending from one end of said upper member, a shorter lower member connected at one end with said L-shaped member, a longer lower member, a curved member connecting the lower members at one end, and an up- 20 right member at the other end of said longer lower member.

a is the upper member, and b is a loop-like portion at one end of same. c d is the L-

shaped member, pendent from the other end of the member a.

25 e is the shorter lower member connected at one end to the member c d.

g is the longer lower member, which extends over the portion d of the member c d.

30 f is a hook-like curved member which connects the adjacent ends of the members e and g, and h is an upright member on the prolonged end of the member g, this upright member having at its extremity a loop-like portion i.

35 I claim—

The design for a clip-hook substantially as herein shown and described.

In witness whereof I have hereunto signed my name this 20th day of November, 1899, in 40 the presence of two subscribing witnesses.

ARTHUR HENRY KINCEY.
